(57) **CLAIM**

The ornamental design for a water dispenser appliance, as shown and described.

DESCRIPTION

FIG. 1 is a front and right side perspective view of a water dispenser appliance showing our new design;

FIG. 2 is a front elevational view thereof;

FIG. 3 is a top plan view thereof;

FIG. 4 is a bottom plan view thereof; and,

FIG. 5 is a right side elevational view thereof, the left side being a mirror image thereof.

The broken lines shown in the drawing disclosure are for illustrative purposes only and form no part of the claimed design.
